UNITED STATES PATENT OFFICE.

JOHN H. ADAMS, OF SEATTLE, WASHINGTON.

PAPER-RULING MACHINE.

1,260,999.

Specification of Letters Patent.

Patented Apr. 2, 1918.

Application filed April 3, 1916. Serial No. 88,465.

To all whom it may concern:

Be it known that I, JOHN H. ADAMS, a citizen of the United States, and resident of the city of Seattle, county of King, State 5 of Washington, have invented certain new and useful Improvements in Paper-Ruling Machines, of which the following is a specification.

My invention relates to apparatus for ruling paper. It is particularly adapted for use in small printing shops, where a large ruling machine would be unnecessary.

The object of my invention is to produce a machine which will efficiently rule paper 15 in any desired form, and a machine which will be cheap in construction and operation.

My invention consists of the novel parts and combinations of parts which are shown in the drawings, and which will be herein- 20 after described in the specification, and defined by the claims terminating the same.

In the drawings I have shown my invention in the form which is now preferred by me.

25 Figure 1 is a side view of my device, with parts broken away.

Fig. 2 is a fragmentary side view of a modification of my invention.

Fig. 3 is a plan view of my preferred 30 form, parts thereof being broken away.

Fig. 4 is a transverse section through the preferred form, taken just to one side of the center.

Fig. 5 is a side view of a second modification, parts being omitted.

In my invention I employ, as a means for feeding the paper to the ruling mechanism, a belt and a series of cords, and deflect the runs of belt and cords between which the 40 paper is placed laterally at the ruling position, thereby securing a better grip of the belt and cords upon the paper, and a more accurate feed of the paper through the device.

45 The belt 6 is placed about rollers 21, which are suitably supported upon the frame, herein shown as journaled upon two standards 10 and 11, secured at opposite ends of the base 1. The cords are passed over rollers 20, which are journaled upon the same frame members, adjacent the rollers 21. For convenience in tightening these parts, one roller of each pair is mounted so as to be adjustable, the manner of adjustment shown being 50 the use of journal blocks 3, mounted to slide

in recesses 32 formed in standard 11, and adjustable by means of threaded rods 31.

Rollers 20 at one end of the device, are connected by gear wheels 23, so as to produce like movement in the belt and cords. 60 In the construction shown in Figs. 1 and 2, I have provided a plate 5 which is convexly curved and lies between the two runs of the belt, and is positioned so as to deflect the inner runs of both belt and cords toward, 65 and substantially into contact with the outer or return run of the cords. By doing this the cords press more firmly upon the belt, and a better feeding grip and hold of the paper is secured.

70 The ruling mechanism is located to act upon the paper while passing over this deflecting plate 5. As herein shown this ruling mechanism consists of a series of pens 7 carried by bar 71, which is mounted upon standards 43 located one at each side of the belt.

The table 5, in the construction shown in Fig. 1, is a flexible plate, having its ends bearing upon transverse bars 13, which extend across between the two standards 10 and 11, respectively. The table is secured against rising from these bars 13 by means of slots 52 in the plate, and pins 51 having heads thereon, which pass through said slots 80 and are secured in the bars 13. The central portion of this plate is adjustable transversely of the movement of the belts, so as to thereby adjust the position of the paper at the time of ruling, and also the tension 85 applied to the belts.

A bar 41 is shown as extending transversely of the belts at this point, this being adjusted by a couple of jack-screws 4. In the form of construction shown in Fig. 2, the 95 ends of this plate are unsupported. The bar 41, which engages the under side thereof, is similarly adjustable by jack-screws 4. As the ends of the table are unsupported, they tend to spring upward, thus producing 100 a clamping effect throughout their length.

To insure the cords 61 maintaining the position in which they are placed, the rollers 20 should be grooved, as is shown in Figs. 3 and 4. The cords will thus be maintained 105 in whatever groove they are placed. The ruling pens 7 pass between the cords in contact with the paper.

In Fig. 5 a slightly different construction is shown, this employing a roller 54 at the 110

point where the ruling occurs, this being adjustable by headed bolts 4, as in the other forms of construction.

A feeding platform 14 is placed at one end 5 of the device, and a corresponding delivery platform 15 at the other end. The paper is fed in over the platform 14, is caught between the belt and the cords, and carried under the ruling pens 7, being delivered at 10 the platform 15.

What I claim as my invention is:

1. An apparatus for ruling paper comprising a flexible table, two pairs of synchronously rotating rollers one above the 15 other at opposite ends of said table, a belt passing about the lower roller of each pair, with its upper portion passing over and deflected by the table, a series of cords passing about the upper roller of each pair, the 20 lower portion of said cords passing over and being deflected by the table, and means for vertically adjusting the table to regulate the tension upon said belt and cords, and a ruling pen located above the highest 25 point of said table.

2. An apparatus for ruling paper comprising a flexible table, two pairs of synchronously rotating rollers one above the other at opposite ends of said table, a belt 30 passing about the lower roller of each pair, with its upper portion passing over and deflected by the table, a series of cords passing about the upper roller of each pair, the lower portion of said cords passing over 35 and being deflected by the table, means for vertically adjusting the table, a ruling pen located above the highest point of said table, and means for adjusting the distance between said pairs of rollers to regulate the 40 tension upon said belt and cords.

3. An apparatus for ruling paper comprising a base, two pairs of standards secured upon said base, a pair of rollers jour-

naled in one pair of standards, two pairs of bearings slidably mounted in the second 45 pair of standards, a pair of rollers journaled in said bearings, means for regulating the distance between said journal bearings of opposite standards, a flexible table extending between said pairs of rollers, said table 50 extending above the plane defined by tangents to the lower surfaces of the upper rollers of each pair, means for vertically adjusting said table, a ruling pen located above the highest point of said table, a belt 55 passing about the lower roller of each pair, the upper course of said belt passing over said table, and a series of cords passing about the upper roller of each pair, the lower course of said cords passing over said 60 table.

4. An apparatus for ruling paper comprising a base, two pairs of standards secured upon said base, a pair of rollers journaled in one pair of standards, two pairs 65 of bearings slidably mounted in the second pair of standards, a pair of rollers journaled in said bearings, means for regulating the distance between said journal bearings of opposite standards, a flexible table extending between said pairs of rollers, said table 70 extending above the plane defined by tangents to the lower surfaces of the upper rollers of each pair, the ends of said table being slidably secured to said standards, 75 means for vertically adjusting said table, a ruling pen located above the highest point of said table, a belt passing about the lower rollers of each pair, the upper course of said belt passing over said table, and a series of 80 cords passing about the upper rollers of each pair, the lower course of said cords passing over said table.

Signed at Seattle, Washington, this 23rd day of March, 1916.

JOHN H. ADAMS.
